LOOSE-LEAF BINDER

Edward F. Buenger, Oak Park, and Charles V. St. Louis, Chicago, Ill., assignors to Wilson-Jones Company, Chicago, Ill., a corporation of Massachusetts

Application June 20, 1940, Serial No. 341,432

1 Claim. (Cl. 129—13)

This invention relates to loose leaf binders of the type provided with a locking post, and particularly to the structure for releasing the locking post to permit expansion or separation of the back sections of the binder.

It is an object of this invention to provide a locking post with releasing means permanently secured thereto that will require a minimum of space, is simple and inexpensive to make and assemble in the binder, and is efficient in operation. Other objects of this invention will become apparent upon reading the following description, taken in conjunction with the accompanying drawings, in which:

Figure 1 is a perspective view of a loose leaf binder embodying the invention;

Figure 2 is a perspective view of the back sections of the binder in disassembled position;

Figure 3 is a fragmentary cross sectional view taken through the locking post;

Figure 4 is a cross sectional view taken along the line IV—IV of Figure 3; and

Figure 5 is a fragmentary perspective view showing the post releasing means.

In the drawings, the reference numerals 2 and 3 indicate a pair of back sections to which cover members 4 and 5 are hinged in any suitable manner as indicated at 6 and 7. The back sections are provided with sheet retaining posts 8 upon which a plurality of sheets 9 may be impaled. The posts 8 are illustrated as being telescopic, but it will be understood that any suitable type of sheet retaining posts may be used. The back section 2 is provided at its ends with flanges 10, which serve to guide the back section 3 when the back sections are telescoped.

The back section 3 is provided with a male post section 11 which is adapted to be engaged by a female post section 12 mounted on the back section 2. The female post section 12 is provided at its free end with a taper 13 which serves to retain an inner member 14 inside the female post section 12.

The inner member 14 is provided with a plurality of circumferential recesses 15 in each of which a ball 16 is positioned. The inner member 14 is provided with a shoulder 17 intermediate its length and a coil spring 18 encircles the narrow portion of the member 14 and exerts constant pressure against the shoulder 17 to urge the member 14 toward the tapered end 13 of the

female post section. The taper 13 forces the balls 16 into contact with the male post section 11 to lock the post sections against movement in an outward direction. In order to release the post sections from locking engagement so that they may be moved outwardly relative to each other, it is necessary to move the inner member 14 against the action of the spring 18 so that the balls 16 are moved out of contact with the tapered end 13 of the female post section 12.

The narrow portion of the member 14 projects through the top of the female post section 12 and extends a slight distance above the top wall 19 of the back section 2, as indicated at 20.

The section 20 is apertured transversely as indicated at 21. A lever 22 has one end extending through the aperture 21 and has an intermediate portion bent in U-shape as indicated at 24. A strap 25 welded or riveted to the top wall 19 engages the portion 24 of the lever and enables the portion 24 to serve as a fulcrum so that when the end 26 of the lever is lifted it lifts the member 14 a sufficient distance to release the locking balls 16 from locking engagement with the male post section 11. When the end 26 is released the spring 18 forces the member 14 back into locking position.

While we have described a preferred embodiment of our invention in detail, it will be understood that the description thereof is illustrative, rather than restrictive, as many details may be modified or changed without departing from the spirit or scope of our invention. Accordingly, we do not desire to be restricted to the exact construction described, except as limited by the appended claim.

We claim:

In a loose leaf binder, a back section provided with a top wall, a female post section depending from said top wall, a locking member positioned in said female post section and extending above said top wall, and a U-shaped lever having the intermediate portion connecting the two legs of the U-member pivoted to said top wall, said lever having means projecting from the end of one leg engaging said locking member and the other leg of said U-member being liftable to release said locking member from locking engagement.
